UNITED STATES PATENT OFFICE.

RAYMOND E. CRANE, OF CAMERON, WEST VIRGINIA.

SANITARY FIXTURE.

1,039,903.

Specification of Letters Patent.

Patented Oct. 1, 1912.

Application filed August 10, 1911. Serial No. 643,344.

To all whom it may concern:

Be it known that I, RAYMOND E. CRANE, a citizen of the United States, residing at Cameron, in the county of Marshall and 5 State of West Virginia, have invented certain new and useful Improvements in Sanitary Fixtures, of which the following is a specification.

My invention relates to sanitary fixtures 10 such as a wash basin, of a type such as a lavatory or drinking fountain, and is adapted more specifically for that particular class of such fixtures which stand slightly away from the wall, permitting of the cleaning of 15 the wall behind the fixture.

The objects of my invention are to support said sanitary fixtures by a hanger which is simple to install and which will permit an adjustment for raising or lowering either 20 side of the lavatory should the hanger not be installed level, or should the lavatory be warped so that when the hanger is level the slab would not look right.

I attain these objects in the method shown 25 in the accompanying drawings, in which—

Figure 1 is a perspective view facing the lavatory from a little to the right side of a straight front view. Fig. 2 is a view, partly 30 in section, showing an arm of the bracket and a sectional view of part of the lavatory, so that the method of attachment of bracket to lavatory can be more readily understood. Fig. 3 illustrates a view, looking from above 35 the lavatory, for the purpose of showing the location of the groove O and the fastening lugs R.

Similar letters refer to similar parts throughout the several views.

The lavatory bracket with its arms A and 40 A' is screwed to the wall by means of screw-holes S—S—S. These arms A and A' are equipped with set-screws B—B—B, both vertically and horizontally directed. The bracket is also equipped with a tongue or 45 holding-lug C. A lavatory, which in this case is circular and with a back, T, is provided at R—R with lugs which are adapted to receive both the vertical and horizontal set-screws B—B. After the hanger is

screwed to the wall, the lavatory tongue 50 groove or holding-slot O is set over the tongue C. The vertical set-screws B—B on each arm are then adjusted until the slab of the lavatory is approximately level. The horizontal set-screws B—B are then made 55 tight and abut against the slanting surface of the lugs at R, thus holding the lavatory from being pulled away from tongue C. This makes a rigid connection, preventing the lifting of the front of the lavatory or 60 of the rear of the lavatory, and provides at the same time an economical and simple method of supporting same. This construction also enables the wall behind the lavatory to be kept perfectly clean. 65

Anyone familiar with the art of manufacturing earthenware lavatories is familiar with the fact that crookedness, owing to shrinkage in firing, is one of the principal difficulties with which such manufacturers 70 have to contend, and the ability to adjust the lavatory by means of set-screws is a very important one, as the plumbing trade will take more readily to a fixture that can be installed by the less skilful class of plumbers, 75 and the saving of time on highly-paid labor which is achieved by my invention is very likely to be underestimated by anyone who has not had experience in such work.

Having described my invention, what I 80 claim therein as new, and desire to secure by Letters Patent, is—

A lavatory or other sanitary fixture, a supporting bracket for same containing two side arms, a three-point bearing from said 85 bracket for the holding of said lavatory, means of adjustment of the elevation of each side of the lavatory, and means for locking said lavatory to the bracket, substantially as described. 90

Cameron, W. Va., Aug. 5, 1911.

In testimony whereof I affix my signature in presence of two witnesses.

RAYMOND E. CRANE.
